CLAIM

The ornamental design for a tongue cleaner, as shown and described.

DESCRIPTION

FIG. 1 is a perspective view of the tongue cleaner showing my new design.

FIG. 2 is a right side elevational view thereof, the left side view being a mirror image of the right side view.

FIG. 3 is a top plan view of the tongue cleaner.

FIG. 4 is a bottom plan view thereof.

FIG. 5 is a front elevational view thereof; and,

FIG. 6 is a rear elevational view thereof.
